L. A. COGSWELL

MARKER FOR LEATHER GRADERS

Filed Oct. 6, 1922

Inventor

Leander A. Cogswell

By Geo. St. Maxwell,
Attest.

UNITED STATES PATENT OFFICE.

LEANDER A. COGSWELL, OF MANCHESTER, NEW HAMPSHIRE, ASSIGNOR TO LACENE MANUFACTURING COMPANY, OF MANCHESTER, NEW HAMPSHIRE, A CORPORATION OF MAINE.

MARKER FOR LEATHER GRADERS.

Application filed October 6, 1922. Serial No. 592,914.

To all whom it may concern:

Be it known that I, LEANDER A. COGSWELL, a citizen of the United States, residing at Manchester, in the county of Hillsboro and State of New Hampshire, have invented an Improvement in Markers for Leather Graders, of which the following description, in connection with the accompanying drawings, is a specification, like letters on the drawings representing like parts.

In the latest evening and grading machines of the Lacene Manufacturing Company (being my machines and those of Elmer P. Nichols and covered by our respective patents and pending applications) particular emphasis is laid upon speed of output, and my latest machine is designated as a speed-up machine in which there is an automatic feed which carries the blanks rapidly, one after the other, into and through the detecting mechanism to be operated upon by the various grading mechanisms, all at as high rate of speed as is possible. This brings into more prominence the problems of momentum, lost motion, etc., and in connection with the marker or stamp it makes desirable a positive means for preventing the tendency to chatter or to continue rotating or swinging at the movement of marking, which would result in stamping upon the leather either a blurred mark or portions of two marks. Accordingly my present invention has for its object the provision of a marker of the kind commonly found in the well-known Nichols patents (for instance in Patent No. 1,130,321, March 2, 1915) provided with means for preventing chattering, swinging or improper motion at the instant of marking the leather.

While my invention may have different mechanical embodiments I have herein shown the same in a very simple form applied to the rotary marker of the Nichols type, but do not intend to restrict my invention thereto except as otherwise required by the claim at the end of this specification.

In the drawings,

Fig. 1 is a longitudinal vertical sectional view taken in the plane of the dotted line 1, Fig. 2, showing the parts up:

Fig. 2 is a vertical cross sectional view taken on the dotted line 2—2, Figs. 1 and 4;

Fig. 3 is a sectional detail similar to Fig.

2 in part, showing the marker down in the position when marking; and

Fig. 4 is a vertical longitudinal sectional view, the same as Fig. 1, excepting that it shows the parts in the position they assume when down.

Mounted on the bridge or cross-head 1, which is a convenient fixed part of the frame of the grading machine, is a sliding member or head 2 (the same as shown in Figs. 6 and 7 of said Nichols patent) in which is pivoted at its lower end a marking wheel or rotary stamp 3 fast on a shaft 4 provided at the end opposite the rotary marker with a pinion 5 by which said marker is rotated to its proper adjustment by a segmental rack 6 at the lower end of a lever 7 pivoted at 8 and caused to swing by an operating link 9 in response to the adjustment of the sliding rack (not shown, but designated as 26 in said patent) to which it is pivoted at 11. All this, together with the further operating connections and parts in the complete machine are described in detail in said patent to which reference is made, and, therefore, further detailed description herein is omitted. Suffice it to say that a long bearing for the slide-head 2 is provided by an extension 12 of the casting 1 to give true vertical movement when the lifter cam and dropper 13 (designated as 65 in said patent) releases the marker and permits it to be instantly driven down with great force and suddenness by the pressure arm 14 and its heavy spring 15 acting with reference to the pivot 16. This vertical drop of the marker takes place just as the rotation of the marker wheel under the swinging adjustment of the rack 6 has taken place, and in fact, it may begin just as this adjustment is ceasing, but has not quite ceased. When operating these machines at low speed, the construction thus far described was usually sufficient, but when operating them at high speed, the momentum of the rotating wheel and the swinging rack and the combination of other motions and forces produces a chatter, or blurring, or double marking. Accordingly, to render this impossible, while yet maintaining the desired speed and keeping the rotary die as the most practical form and the other swinging parts, I fit a stiff plate or post 17 in a slot 18 formed in the bridge casting 1 and pref-

erably tightly fitting said plate or post, the latter being also shown as secured by screws 19. This plate or post at its lower inner side has a tooth or projection 20 to act as a 5 positive stop or lock against cooperating stops or shoulders shown for convenience of construction as pins 21 rigidly secured or driven fast into the stamp wheel 3 so as to project therefrom at the outer face thereof 10 sufficiently to engage in pairs the respective sides of said tooth or stop 20 or to be engaged by said tooth or stop 20, preferably with a close fit. The pins are preferably round and the upper end of the tooth is 15 preferably wedge shape and the position of the tooth is such that it is entirely out of range of said pins when the marking wheel is up and when it is descending and is still being rotated or adjusted but is in range with 20 said pins when the marking wheel is down.

In operation the marking wheel is adjusted as usual by the swinging of the segmental rack 6 on the pinion 5 and this takes place while the parts are up as shown 25 in Fig. 1 and may continue an instant longer, as the wheel begins to fall. The instant, however, that it has fallen so as to bring the upper-most pair of pins into juxtaposition with the teeth or stop 20 the 30 latter enters between said pins, or rather the pins fall on either side of said tooth straddling the same tightly, and positively locking the marking wheel 3 against the slightest chatter or lateral movement at and 35 just before the instant of stamping impact. This restricts the stamping movement absolutely to a true vertical blow on the leather. In some kinds of leather, instead of a steel cutting die, a rubber stamp is 40 necessary, and it will be seen that my invention is equally applicable to both of these kinds of stamping wheels. I have also shown in the drawings a size wheel 77 and its adjacent parts lettered 78, 80, 81, 45 as in said patent. This is turned by hand as stated in said patent, and, therefore, a spring-held ball-and-socket holding device

of the kind shown is sufficient but would be inoperative for the wheel 3. This is because said wheel 3 must be perfectly free to turn for its delicate adjustments and yet when locked the lock must be strongly resistant and positive as the locking takes place at the moment of sudden and intense movement. This movement is not only at 50 the instant of the exceedingly quick down and up stamping movement, but the lock is called upon to resist the quick lateral movement of the swinging parts and the rotating parts. The necessity for instantaneous 55 down and up movement is due to the fact that the stamping takes place without halting the forward feeding movement of the leather blank being stamped. In this type of machine the leather blank never halts or 60 hesitates in its travel from the time it is automatically fed into the machine at one end until it is automatically deposited at the other end after having been measured, stamped, skived and distributed. 70

Claim:

In a machine of the kind described, in combination with the cross head of the frame, a slide mounted for vertical reciprocation on the cross head, a rotary stamp journaled on said slide below the cross head, a series of shoulders arranged in a circle on one side of the rotary stamp, a member rigidly fixed to the cross head and extending downward beside the stamp and close 75 to said shoulders, and a projection on said fixed member extending toward the side of the stamp and inside the circle of shoulders when the stamp is in elevated position and adapted to engage a pair of the shoulders and lock the stamp when the stamp is 80 in depressed position. 85

In testimony whereof, I have signed my name to this specification, in the presence of two subscribing witnesses.

LEANDER A. COGSWELL.
